UNITED STATES PATENT OFFICE.

NICHOLAS A. STATHES AND GEORGE A. STATHES, OF NEW YORK, N. Y.

AUTOMATIC CLOSURE.

Application filed July 2, 1926. Serial No. 120,143.

Our invention relates to certain new and useful improvements in automatic closures for containers in general and particularly for portable liquid containers, and more especially does it relate to closures for the gasoline tanks of automotive engines and automobiles.

It is a well-known fact that the closures now used for automobile gasoline tanks are very unsatisfactory for the reason that, being screwed on the pipe-opening, they either work loose and become lost or are stolen. The loss of the gasoline tank closure results in great inconvenience to motorists because it is very difficult to pick up another one that will fit the opening of that particular tank.

Therefore, our invention is designed to eliminate the possibility of such closures being lost or stolen and has, among others, the following objects in view:

To provide a closure which will be so securely clamped or bolted adjacent the mouth of the opening which it is intended to cover as to be inseparable therefrom;

To provide closure caps for stem openings which will be hingedly connected to the stem;

To provide a closure cap which under all normal conditions, will be held automatically and firmly closed;

To provide closure means for openings which will be inseparably connected to the container, automatic in operation, efficient in use, of simple construction, and easy to manufacture at a comparatively low cost.

Other objects and advantages of our invention will be made clear and apparent as the description proceeds.

Reference is now had to the accompanying drawings which form a part of this application, and in which:

Fig. 1 is a side view of a stem opening carrying our improved closure, parts of same being broken away to show some of the construction in detail.

Fig. 2 is a top view of the closure cap, also showing the lugs or ears whereby it may be hinged either to a clamp collar or to lugs integrally cast with the stem.

Fig. 3 is a vertical sectional view of stem opening on which means for fastening our improved cap are integrally cast.

Fig. 4 is a ring collar adapted to have hinged thereunto our closure cap and then to be clamped to a stem opening.

Fig. 5 shows a modified form of retaining the packing means on the closure cap.

Fig. 6 is a vertical sectional view through the hinged parts of the cap and clamp collar, or through the closure cap and the lugs on the stem, as the case may be. This figure also shows the automatic means provided for keeping the cap in a closed position.

Fig. 7 is a perspective view of one form of the automatic spring means that may be employed to urge the cap in closed position.

Referring now to the drawings for a more detailed description of the construction and operation of the device, numeral 1 represents the stem opening projecting from the gasoline tank of an automobile, not shown, but it may be taken to represent any hollow stem open at the top 2. Encircling the stem 1 is a split collar 3 the open ends of which are bent outwardly to form parallel ears 4. These projecting ears 4 have opposing openings 5 through both of which a threaded bolt is passed and by means of a nut operating on the bolt through the holes on the ears of the collar, the same is drawn tightly and securely around the stem 1.

Diametrically opposite the open ends 6 of the collar 3 and integrally cast with said collar are upstanding lugs or ears 7. The inside faces of the lugs or ears 7 are perpendicular to the top surface of the collar and on the outside thereof. The lugs or ears 7 are provided with opposing holes for the reception of a hinge bolt or rivet 9.

Numeral 10 indicates the closure cap which is provided with a depending annular flange 11, a notch-like outward projection 12 and a pair of downwardly projecting lugs 13. The lugs 13 are provided with holes 14 to correspond with the holes 8 on the lugs 7 of the collar 3. The closure cap 10 is further provided on the inside thereof with a packing means 15 which is held in place either by such means as indicated by numeral 16, Fig. 1, or by the method shown at 17, Fig. 5.

It is important to note here that across the outer and lower sides of lugs 7, and across the outer and upper sides of lugs 13 are webs 18 and 19, respectively. These webs are complementarily curved inside and out, and mated to coact in a manner and for purposes hereinafter described.

Numeral 20 indicates a hair-pin shaped steel spring, the legs of which have been coiled in the manner shown. This spring is adapted to be placed between the lugs 7 in

such a manner as to have the loops 21 register with holes 8, the ends 22 resting against and, under pressure, conforming with the inside curvature of web 18, while the top or 5 looped end 23 of the said spring will rest against, and under pressure, will conform with the inside curvature of web 19 when the device is assembled and in use. The position and action of the spring while the invention 10 is in use is clearly illustrated at Fig. 6.

While the form of spring herein illustrated is preferable, it is obvious that any other form of similarly acting spring means may be used without departure from the 15 spirit of our invention.

Now, having described the structure of the elements of our invention we desire to describe the manner of assembling and applying the same:

20 The spring 20 (or any other spring suitable for the purpose) is placed between the lugs 7 in the manner above described. Then the cap 10 is placed over the collar 3 in such a manner that the lugs 13 will fit over 25 the lugs 7. (This is possible because the lugs 13 are further apart from each other than lugs 7.) Holes 14, by the application of sufficient pressure on cap 10, will come in registry with holes 8, then bolt 9 is inserted and may be secured in place either 30 by bradding the end of the bolt or by a threaded nut co-operating with threads on the end of the bolt. The device then is ready for use and may be clamped around 35 the stem of the opening for which it is desired to serve as a closure.

When it is desired to lift the cap either 40 for the purpose of pouring out the contents or for replenishing the container, the same is accomplished by lifting the cap with the hand against the outward projecting notch 12. When the cap is thus lifted, the web 19 slides over the outer surface of web 18, the spring is tensioned, and when the cap is 45 released it flaps shut and is held shut tight by the spring as shown at Fig. 6. The packing member 15 forms a seal between the cap and the lips of the opening so that there is no danger of the liquid contents of 50 the tank leaking out no matter how much it may be splashed.

At Fig. 3 we have shown the lugs 8 cast integral with the stem. This eliminates the need of the clamping collar 3 and at the 55 same time the clamping means at the lugs 4.

The form of the device illustrated at Fig. 1 is adapted to be used on tanks of automobiles already in use, while the form illustrated at Fig. 3 can be made and fitted on 60 new tanks where our invention is desired to be used.

At Fig. 5 we have illustrated a novel way of holding the packing in place. This consists of forming a constricted groove on the 65 underside of the cap and also forming the

packing in the form of an endless annulus having on the top side thereof a rib or bead of a contour corresponding to the contour of the groove. The packing being made of rubber, or other pliable material can be 70 easily compressed into the groove in which it is held by the force exerted against the walls of the groove by the tendency of the compressed material to expand.

It is thought that the foregoing specification clearly sets forth the many advantages of our device, and it is apparent that we have invented a closure which is novel, efficient and durable, and, although we have herein described and illustrated the preferred embodiment of our invention, it is not the less evident that changes in the details of its construction may be made without departing from the scope of the invention. It is, therefore, to be understood that we do not intend to limit our invention, to the specific details of construction herein shown and described, but changes falling within the scope of the claims may be had in accordance with the spirit and idea of 90 the invention.

What we claim is:

1. An automatically closing cap for the stem openings of automobile gasoline tanks comprising a closure cap, said closure cap being lined with packing material; a split band, the ends of which are bent to form outwardly projecting parallel ears; downwardly projecting lugs on the closure cap and upwardly projecting lugs on the split 100 band; said lugs being perforated and a bolt passing through the perforations and pivotally connecting the band with the closure cap; concavo-convex webs across the lugs on the cap and band forming a housing, a resilient spring in the housing, said spring being tensioned against the webs for the purpose of keeping the closure cap in a downward position.

2. In a device of the character described a 110 container having an opening; a closure cap for said opening, a pair of perforated lugs near the opening and a pair of perforated lugs on the closure cap, concavo-convex webs connecting the top sides of the respective 115 lugs at their lower and upper portions respectively, thereby forming housings; the housing formed by the lugs and web on the closure cap being larger than the similar housing formed by similar means on the 120 container; the closure cap placed over the opening with its lugs embracing the lugs on the container and the aforesaid holes coming in alinement, a bolt hingedly connecting the closure cap to the container, spring means housed by the webs and tensioned thereagainst, the inner surface of the web on the closure cap lapping over the outer surface of the web on the container and co-acting therewith in lapped relation during 125 130

the opening and closing operations of the closure cap.

3. In combination with a receptacle having an opening, a pair of upwardly projecting parallel lugs adjacent the opening, opposing holes near the upper ends of the lugs, a web having an outer convex surface and an inner concave surface bridging the lower portions of the lugs; a closure cap having 10 downwardly projecting parallel lugs, said lugs having opposing holes near their respective lower ends, a web bridging the upper portion of the lugs, said web having its outer surface convexly curved and its inner 15 surface concavely curved; the lugs on the closure cap being further apart than the lugs on the container; the said closure cap fitting over the opening of the container, the lugs on the closure cap enveloping the lugs 20 on the container, the holes on the several lugs being in alinement, a bolt passing through the holes, and a resilient spring around the bolt housed by both of said webs.

4. In combination with a split band having its ends bent outwardly and perforated thereby adapting the same to be securely fastened around the stem opening of an automobile gasoline tank; a closure cap pivotally connected to the band, resilient means 30 employed at the points of connection for closing and keeping closed the cap over the

opening, housing for the spring, said housing being partly on the cap and partly on the band, the two parts being in over-lapping relation and coacting when the cap is being 35 opened or closed.

5. A closure cap for the openings of automobile gasoline tanks comprising a disk adapted to fit over the opening, a projecting thumb-lug on the periphery of the disk, a 40 skirt depending from the disk, a pair of lugs on the skirt the ends of said lugs being perforated and projecting below the lower edge of the skirt; in combination with a split band having the ends thereof bent outwardly and perforated, a pair of lugs on the band, the ends of said lugs being perforated and projecting upwardly and beyond the upper edge of the band, means hingedly connecting the lugs of the cap and band, a 45 50 looped hair-pin spring surrounding the connecting means, complementary webs on the respective lugs for housing the connecting means and the spring and for the further purpose of providing constricting walls for 55 keeping the spring tensioned whereby the cap is kept closed under all normal conditions.

In testimony whereof we have subscribed our names hereto.

NICHOLAS A. STATHES.
GEORGE A. STATHES.
